GAME APPARATUS

Francis T. Czajkowski, Morrisville, Pa., assignor
of one-half to Rose Marie Swangler, Morris-
ville, Pa.

Application April 8, 1936, Serial No. 73,364

3 Claims. (Cl. 273—105)

The invention relates to a game apparatus and has for its primary object to provide an apparatus of this character, which on the bouncing of a ball through skill the same can be cupped or trapped, thereby rendering amusement and affording pleasure in the playing of a game thereby.

Another object of the invention is the provision of an apparatus of this character, wherein the receiver for the ball is so supported that it will totter when the ball on the bouncing thereof makes contact therewith thus making it difficult for the cupping or trapping of the ball when bounced, considerable skill being required for the cupping or trapping of such ball on the bouncing 15 of the same upon a playing surface.

A further object of the invention is the provision of an apparatus of this character, which is simple in construction, requiring skill in the playing thereof, affording attraction and amusement during the playing of a game and inexpensive to manufacture.

With these and other objects in view, the invention consists in the features of construction, combination and arrangement of parts as will be 25 hereinafter more fully described, illustrated in the accompanying drawing, which discloses the preferred embodiment of the invention and pointed out in the claims hereunto appended.

In the accompanying drawing:

30 Figure 1 is a side elevation of the game apparatus showing diagrammatically the manner of the playing of the ball for the bouncing thereof to be trapped in a cup or receiver therefor.

Figure 2 is a fragmentary top plan view showing the goal line and the relation of the receiver or cup for the ball when bounced.

Figure 3 is an enlarged vertical sectional view through the cup or receiver showing by full lines the normal position thereof and by dotted lines 40 a tilted position.

Figure 4 is a top plan view of the cup or receiver.

Figure 5 is a top plan view of the support for the receiver or cup.

45 Figure 6 is a top plan view of a modified form of the cup or receiver.

Figure 7 is a top plan view of a further modification of a cup or receiver.

Similar reference characters indicate corresponding parts throughout the several views in the drawing.

Referring to the drawing in detail, A designates generally a playing surface, it having a goal line B marked thereon and upon this surface at the 55 required distance from the goal line B is ar-

ranged a cup or receiver 10, it having a marginally flanged open mouth 11 while provided in its closed bottom is a central opening 12, the said bottom 13 being of concavo-convexed formation. The cup or receiver 10 is supported upon a disk-like base 14, it having a swiveled pin 15 centrally thereof and rising a distance therefrom. The pin 15 is loosely accommodated in the opening 12 in the bottom 13 of the cup or receiver 10.

5 Usable with the cup or receiver 10 is a rubber ball 16 which is tossed in a manner to effect a bouncing thereof upon the playing surface A between the goal line B and the cup or receiver 10 for the purpose of having the ball drop into the open mouth 11 of said cup or receiver, it being 10 required that skill be exercised in the proper bouncing of the ball for the trapping thereof within the cup or receiver and in doing this a 15 score is had under a game as played by the apparatus.

20 The cup or receiver 10 is extremely sensitive to contact of the ball 16 by reason of the swivel and tilting mount thereof.

In Figure 6 of the drawing there is shown a slight modification of the receiver or cup, wherein the conformation of the latter is of octagon formation, otherwise this cup or receiver 17 is similarly constructed to the cup or receiver 10.

In Figure 7 of the drawing there is shown a still further modification, wherein the cup or receiver 18 is of square formation in the body thereof.

30 The cup or receiver can be made of different sizes so as to accommodate balls of varying sizes and the ball 16 as used is of the plain rubber type. 35 There can be assigned to each player a given number of balls and on the cupping or trapping of each in the playing of the apparatus renders a particular score in the playing of a game thereby.

40 A cup or receiver of the apparatus can be made from any suitable material, as for example, Bakelite, metal, tin, hard rubber or other substances.

In the playing of the apparatus the ball is tossed or thrown from the goal line B, one bounce of 45 the ball being allowed only and by the cupping of the bounced ball affords a particular score for the player in the playing of the apparatus.

What is claimed is:

1. In an apparatus of the character described 50 a pegged support, and a receiver pivoted to the peg of said support for tilting movements, and having a rounded centrally perforated bottom.

2. In an apparatus of the character described 55 a pegged support, and a receiver pivoted to the

peg of said support for tilting movements, and having a rounded centrally perforated bottom, and also a receiving mouth opening.

3. In an apparatus of the character described, 5 a support having an upstanding peg, a receiver having a substantially convex-shaped bottom

contacting the support, and said bottom having a central perforation for receiving the peg therethrough, the perforation being of greater diameter than the peg.

FRANCIS T. CZAJKOWSKI.
